UNITED STATES PATENT OFFICE.

REGINALD ARTHUR COUSANS AND LOUIS BERTRAM COUSANS, OF LINCOLN,
ENGLAND.

AIR-COMPRESSOR.

No. 852,541.

Specification of Letters Patent.

Patented May 7, 1907.

Application filed November 30, 1903. Serial No. 183,305.

To all whom it may concern:

Be it known that we, REGINALD ARTHUR COUSANS and LOUIS BERTRAM COUSANS, subjects of the King of Great Britain and Ireland, both residing in Lincoln, England, have invented certain new and useful Improvements in and Relating to Air-Compressors for Blowing Organs, of which the following is a specification.

This invention relates to air compressors for blowing organs and has for its object to provide means whereby a series of air compressors of the compound centrifugal fan type may be employed for this purpose with efficiency, and whereby the end thrusts peculiar to single inlet centrifugal fans will be eliminated or counteracted, means being also provided for allowing of separate air reservoirs in an organ being supplied with air simultaneously at the different pressures required for each reservoir.

According to this invention where a number of single inlet fans are mounted upon the same spindle we arrange that the inlet of a certain number of such fans shall be on the opposite side to those of the remainder, or we provide in the casings suitable air passages or trunks which will convey the air delivered at a certain pressure from one fan to the oppositely disposed inlet of the adjacent or other fan or fans, the air when compressed to a higher pressure due to the efforts of the said fans being delivered to the oppositely disposed inlets of another or other for the purpose of being raised to the final pressure required. It will be seen that these air passages or trunks may be tapped and connected separately to the separate and distinct air reservoirs of an organ for the purpose of withdrawing and utilizing air at the different pressures corresponding to each such passage in such reservoirs simultaneously. The end thrust due to single inlet fans will be entirely eliminated where an equal number of fans are employed, and where an odd number are employed there will only remain the end thrust of one fan which will be so small as to be usually neglected.

Further the invention also provides, in combination with the above construction, means for insuring the working of the fans without noise and with a steadier inflow of air, this being accomplished by providing the inlet or a number of inlets to the first fan of

the series with automatically lifting valves 55 the function of which is not to act as non-return valves when the fans are at rest, but to damp or deaden the noise of the inflowing air and prevent the noise caused by the rotation of the fans when they are working but 60 not sucking in air (the outlet valve, leading to the organ reservoir, being closed). It is at this time that the organ is not being played and it is most essential that the blower should be silent.

We have illustrated in the accompanying drawings a construction and arrangement of compound fan made in accordance with this invention.

Figure 1 shows two fans mounted and 70 driven by one spindle, the view being a longitudinal section. Fig. 2 is a perspective view of Fig. 1 showing the passages for air trunks arranged at the side. Fig. 3 is a similar view to Fig. 1 showing four fans. 75 Fig. 4 is a perspective view of the fan shown in Fig. 3, and means for simultaneously distributing air at different pressures to four distinct organ reservoirs.

Referring to Figs. 1 and 2, *a* is the driven 80 shaft or spindle upon which are mounted two fans *f f'*; the fan *f* draws air from an inlet *b* on the left hand side through an inlet chamber *b'* to which the air has access through a flap valve *c* adapted to be opened by the 85 suction of the fan. These valves may be conveniently mounted upon hinge pins *c'* and need not be air tight, as they are not destined to prevent back flow of air. While the organ is playing air is being sucked 90 through the inlet and the valve is held open by the current of air. As soon as the organ ceases playing it is important to suppress the sound caused by the rotating of the fans and the disturbance of the air within the 95 casing. As the fans are not sucking air at this time the valve automatically closes, cutting off the noise which would otherwise be considerable. A number of these inlets may be arranged in the base of the inlet 100 chamber. The fan *f* delivers air through openings *n* through the periphery of a partition *o* (said openings leading the air parallel to the axis) into a chamber *d* from which the air compressed say to two inches pressure is delivered by passages or air trunks 105 *e e* to a chamber *g* on the opposite side of fan *f'* so that the air from the chamber *g* is

drawn in or delivered to the fan f' by an opening h disposed oppositely to the opening b of the fan f , the fan f' delivers air to the chamber j compressed to a further stage, say 4 inches, the discharge from fan f' being passed into the chamber j through the apertures n' in a partition o' similar to that described in reference to the first fan. These apertures draw off the air in the same direction as the shaft and at different points around the fan, thus distributing the flow over a larger area, and effectively minimizing any tendency to produce noise in working, further these openings having a similar effect in minimizing any violent flow of air in the intermediate chamber.

Fig. 3 illustrates a modified construction showing a spindle carrying four fans, the arrangement of chambers and air trunks, partitions and passages is very similar to that shown in Fig. 1, but modified to suit the use of four fans, for instance the air delivered from the fan f^3 will be conducted by a passage k in a trunk e to the opposite inlet of the fan f^4 and the air from the chamber l into which fan f^4 delivers will be conveyed by a trunk k' to the inlet of fan f^5 disposed on the same side or in the same direction as that of fan f^3 , and the air delivered from fan f^5 will be delivered by an air trunk k^2 to an oppositely disposed inlet of the fan f^6 and delivered from the said fan f^6 at the final pressure into a chamber m .

By this arrangement the use of a number of single inlet fans on the same spindle is rendered possible for the purposes of the invention as the end thrusts of the various fans will be counterbalanced or eliminated, while the final delivery of air will be at a pressure equal to the efforts of the several fans combined. As shown in Fig. 4, the air trunks between the inlets and outlets of the fans will provide for the drawing off therefrom simultaneously of air at different pressures as may be required and as will be especially useful for organ blowing purposes, the air at such different pressure being led to the separate and distinct air reservoirs of an organ so as to be capable of simultaneous use. For instance the air at say 2 inches will be supplied by the air trunk p' to the reservoir q' , while air trunks p^2 p^3 and p^4 will supply air respectively at say 4, 6 and 8 inches to the reservoirs q^2 , q^3 and q^4 . The air may be

drawn from the several reservoirs as needed by pipes Q' Q^2 Q^3 and Q^4 leading to different parts of the organ.

The most important function of this improvement is in the maintaining of a quantity of air at the desired high pressure with a minimum of noise. Quiet running is facilitated by the arrangement of the fans in the center of the space within their several chambers, and ease of running is also determined by the fact that they do not make contact either at their edges or their sides with the casing. Each fan is preferably formed with a rear disk plate r and a front annular plate s the cut out central portion of which forms the inlet opening, the blades being held between the two plates in any usual or suitable manner. It will be apparent therefore that substantially the entire chamber of each fan is filled with compressed air and the pressure of the air at the rear side of the disk r is such as to cause a considerable axial thrust in the direction from this rear plate toward the inlet. This thrust occurs to such an extent as to seriously interfere with the regular and quiet running of the compressor unless it be counterbalanced in whole or in considerable part by the arrangement described. Each of the fans performs substantially an equal share of the work of raising the pressure, and therefore the axial thrust of each is substantially the same. The dividing of the compression into these successive stages therefore assists in the reduction of the axial thrust even where there is an odd number of fans.

What we claim as our invention and desire to secure by Letters Patent is:—

An organ blower including in combination a casing, a fan within said casing, and a silencing valve mounted at the inlet to the casing and adapted to prevent the escape of the noise made by the movement of the fan and the air within the casing when the fan is rotating without substantial suction through the inlet.

In witness whereof, we have hereunto signed our names in the presence of two subscribing witnesses.
